(57) **CLAIM**

The ornamental design for a coffee pod, as shown and described.

DESCRIPTION

1. Coffee pod

1.1 is a side view of a coffee pod, showing my new design;

1.2 is a top view thereof;

1.3 is a bottom view thereof;

1.4 is a top perspective view thereof; and

1.5 is a bottom perspective view thereof.

A round pod with a collar and conical receptacle having three small protrusions on the inside close to the bottom; all side views are identical.
